UNITED STATES PATENT OFFICE.

HAROLD J. BRADT, OF PONTIAC, MICHIGAN.

DISK WHEEL.

Application filed July 1, 1921. Serial No. 481,777.

To all whom it may concern:

Be it known that I, HAROLD J. BRADT, a citizen of the United States of America, residing at Pontiac, in the county of Oak-
5 land and State of Michigan, have invented certain new and useful Improvements in Disk Wheels, of which the following is a specification, reference being had therein to the accompanying drawings.

10 This invention relates to disk wheels for motor vehicles and my invention aims to provide a wheel body that may be built about a well known type of automobile hub, the wheel body being made of metal in con-
15 tradistinction to wood and wire spokes.

My invention further aims to furnish a disk wheel with a demountable rim, which may be quickly attached to the disk body of the wheel and as readily detached. The
20 holding means for the demountable rim is such as to positively clamp the rim on the disk so that it cannot become laterally displaced nor creep circumferentially of the disk.

25 My invention further aims to provide a disk wheel having a demountable rim wherein in the periphery of the disk is expandible by the rim fastening means to cause the periphery of the disk to bind against the rim and
30 attain a double clamping action of the wheel body relative to the demountable rim.

A further object of my invention is to provide a demountable and quick detachable rim for a disk wheel and the devices em-
35 ployed for holding the wheel disk body and rim are free from injury by the ordinary use, durable and highly efficient as a rim fastening means.

The construction entering into my wheel
40 hub will be hereinafter described and then claimed, and reference will now be had to the drawings, wherein—

Figure 1 is an elevation of the inner side of the disk wheel devoid of a tire;

45 Fig. 2 is an elevation of a portion of the outer side of the disk wheel;

Fig. 3 is a cross sectional view taken on the line III—III of Fig. 2;

50 Fig. 4 is a vertical cross sectional view of the disk wheel devoid of a tire;

Fig. 5 is a plan of the inner wall of a portion of the disk wheel;

Figs. 6 and 7 are views, in elevation, of modified forms of disk wheels; and

55 Fig. 8 is an enlarged cross sectional view taken on the line VIII—VIII of Fig. 6.

In the drawings the reference numeral 1 denotes an ordinary and well known type of hub having a peripheral flange 2 which ordinarily assists in supporting the wooden spokes of a wheel, but I use this flange for holding a disk body 3 having a central opening 4 to receive the hub 1. The disk body 3, adjacent the opening 4, has a series of pressed out apertured bosses 5 extending into recesses 6 which I provide therefor in the inner face of the flange 2. Mounted on the hub 1 is a retaining plate 7 and the wall of the disk is sandwiched between said plate and the flange 2. The retaining plate 7 is apertured and extending through the apertures, the bosses 5, and apertures of the flange 2 are bolts 8 provided with nuts 9, said bolts and nuts clamping the disk body between the retaining plate 7 and the flange 2. The pressed out bosses 5 will co-operate with the flange 2 in supporting the disk body relative to the hub 1, and the disk body obtains a more firm purchase between the retaining plate and the flange by reason of the bosses.

The central part of the disk body 3 is dished, as at 10 to receive the flange 2 and said body is disposed at an angle intersecting the vertical plane of rotation of the wheel. The outer or marginal edges of the disk body are curved to present a vertical wall 11; reamed to afford an annular shoulder 12, and stamped to provide a peripheral flange or inner rim 13. Considering the disk body in cross section, the peripheral flange 13 is disposed at a right angle to the wall 11, with the shoulder 12 at the juncture of said flange with the wall. The peripheral flange overhangs the disk body 15 and said flange has its edge slotted, as at 14, so that it may be expanded. The disk body can be stamped from pressed steel, rolled or otherwise produced and the cross sectional shape of the disk body contributes to the rigidity of the wheel as a whole.

The reference numeral 15 denotes a tire holding rim adapted to slide on to the flange 13 and snugly fit thereon. The inner wall of the rim 15 has an annular beveled rib 16 to fit and wedge on the annular shoulder 12 of the disk body, and to retain the rim on the flange 13 and expand said flange against the inner wall of the rim, I employ novel fastening means.

First, there is a wedge ring 17, having its peripheral edge beveled, as at 18 to en-

gage the edge of the flange 13 and expand said flange against the inner wall of the rim 15, when the wedge ring is drawn towards the wall 11 of the disk body. Connected to the wedge ring 17 are a plurality of bolts 19 having threaded ends extending through openings 20 in the wall 11, and on said bolts are retaining washers 21 and nuts 22. The retaining washers 21 are adapted to overlie the outer wall of the rib 16 and retain said rib on the shoulder 12. In order that the rim 15 may be quickly removed from the disk body, without completely removing the nuts 22 and the washers 21, said washers have facets 23 which may be turned into parallel registration with the shoulder 12, and thus permit of the rim 15 being pulled outwardly off of the shoulder 12. Otherwise, the washers overlie the rib 16, as shown in Fig. 2 and retain the rim 15 on the disk body. When the nuts 22 are tightened, it is obvious that the wedge ring 17 is drawn towards the wall 11 and by reason of the flange 13 being slotted portions thereof may expand or be distended to clamp against the inner wall of the rim 15 and firmly clamp the rim relative to the disk body.

For fear that the rim may work loose and tend to shift circumferentially of the flange 13, I provide the shoulder 12 with a pressed out portion or lug 24 which fits into a notch or recess 25 provided therefor in the rib 16, as best shown in Figs. 2 and 3.

The disk body 3 has an oblong opening 26 providing clearance for an air inlet valve 27 carried by a pneumatic tire 28 that may be mounted on the rim 15.

In some instances, I may use short bolts 29 and nuts 30 for holding the retaining washers 21 relative to the wall 11, as shown in Fig. 8, and instead of using the wedge ring 17 I may place an expandable band or ring 30 against the inner wall of the flange 13 and expand or contract the band or ring, either by a turn-buckle 32 as shown in Fig. 6 or by a leverage device 33, as shown in

Fig. 7. The expandable band or ring may have a portion thereof anchored relative to the flange 13, as at 34, so that the band or ring will at all times be in engagement with the disk body for expanding the flange 13 of said body against the inner wall of the rim 15.

It is thought that the manner of mounting and dismounting the rim relative to the disk body will be apparent without further description, and while in the drawings, there are illustrated the preferred embodiments of my invention, it is to be understood that the structural elements are susceptible to such variations and modifications as fall within the scope of the appended claims.

What I claim is:—

1. In a disk wheel, a disk having a shoulder and flange, a rim on the flange of said disk, a rib on said rim against the shoulder of said disk, a ring adapted to engage the flange of said disk and distend the flange against said rim to clamp said rim thereon, and means carried by said ring and bearing against said rib adapted for drawing said ring towards said disk.

2. In a wheel having a body and a demountable rim, the body of the wheel having a configuration permitting of it being distended to clamp the rim on the body, complementary means circumferentially of the rim or wheel body preventing lateral shifting of the rim in one direction relative to the wheel body, and means extending transversely of the wheel body and engaging said complementary means at intervals adapted to simultaneously cause said body to be distended against the rim and prevent lateral shifting of the rim in an opposite direction relative to the wheel body.

In testimony whereof I affix my signature in presence of two witnesses.

HAROLD J. BRADT.
